(57) **CLAIM**

The ornamental design for a splash shield, as shown and described.

DESCRIPTION

FIG. 1 is a perspective view of a splash shield illustrating a new design.

FIG. 2 is a front elevation view of the splash shield shown in FIG. 1.

FIG. 3 is a rear elevation view of the splash shield shown in FIG. 1.

FIG. 4 is a top view of the splash shield shown in FIG. 1.

FIG. 5 is a bottom view of the splash shield shown in FIG. 1.

FIG. 6 is a right-side elevation view of the splash shield shown in FIG. 1; and,

FIG. 7 is a left-side elevation view of the splash shield shown in FIG. 1.

Shade lines shown in the accompanying drawings of FIGS. 1-7 represent surface contour only and not texture, color shading, or surface ornamentation. Broken lines shown in the accompanying drawings of FIGS. 1-7 represent structure that is not part of the claimed design, but rather illustrate the environment in which the design is used.
